UNITED STATES PATENT OFFICE.

FRANK SCHILLING, OF MUNCIE, INDIANA, ASSIGNOR TO THE MUNCIE GLASS COMPANY, OF SAME PLACE.

DESIGN FOR A BOTTLE.

SPECIFICATION forming part of Design No. 30,664, dated May 2, 1899.

Application filed March 20, 1899. Serial No. 709,857. Term of patent 7 years.

To all whom it may concern:

Be it known that I, FRANK SCHILLING, a citizen of the United States, residing at Muncie, county of Delaware, and State of Indiana, have invented and produced a new and original Design for Bottles, of which the following is a specification, reference being had to the accompanying drawings, forming a part thereof, and wherein like letters of reference indicate corresponding parts in the several views, and in which—

Figure 1 is a rear elevation of a bottle, showing my new design. Fig. 2 is a front elevation. Fig. 3 is a side elevation; and Fig. 4 is a section on the line 4 4, Fig. 1.

As shown in the drawings, the leading or material feature of my design consists of a bottle having the rounded front face A and the rounded or curved side faces B. The rear face C of the bottle is flat in a vertical plane and is connected to the side faces by the beveled edge portions D. These beveled edge portions extend from the bottom vertically up to the shoulder of the bottle, where the bevel is curved, as shown at E, extending entirely across the rear face in a curve parallel to the curve of the shoulder of the bottle to the bevel on the opposite edge, as

plainly shown in Fig. 1. The shoulder F of the bottle is formed in a graceful sloping curve. The point of connection between the shoulder and body of the bottle is rounded into a curve parallel with the curve E in the bevel portion. On the front face of the bottle is formed a bead G, which is a continuation of the edge line of the bottle. This bead is curved substantially the same as the curve of the shoulder and is provided with an upwardly-extending point H, located on the vertical axis of the bottle and just below the neck portion. There is a similar bead I, located in the same relative position on the rear face of the bottle, provided with a similar point K.

Having thus described my invention, what I claim as new, and desire to secure by Letters Patent, is—

The design for a bottle, substantially as shown and described.

In testimony whereof I have hereunto set my hand in the presence of two witnesses.

FRANK SCHILLING.

Witnesses:

EDWARD O. WARD,
ISAAC HUMPHREY.
